UNITED STATES PATENT OFFICE

160,071

POURING SPOUT FOR CARDBOARD
MILK CONTAINERS

Joseph Cicio, Sr., Rockford, Ill.

Application January 10, 1949, Serial No. 152

Term of patent 14 years

(Cl. D58—26)

To all whom it may concern:

Be it known that I, Joseph Cicio, Sr., a citizen of the United States, residing at Rockford, in the county of Winnebago and State of Illinois, have invented a new, original, and ornamental Design for a Pouring Spout for Cardboard Milk Containers, of which the following is a specification, reference being had to the accompanying drawings, forming part thereof.

In the drawings:

Fig. 1 is a side view of a pouring spout for cardboard milk containers, showing my new design;

Fig. 2 is a top view thereof, and

Fig. 3 is a front view thereof.

The dominant features of the design are those shown in full lines.

I claim:

The ornamental design for a pouring spout for cardboard milk containers, substantially as shown and described.

JOSEPH CICIO, Sr.
